[57] ABSTRACT

A displacement-electric signal converter having a pair of displacement detecting elements the impedances of which vary in accordance with a displacement, a rectifier including a bridge circuit, first and second capacitors, an oscillator for supplying AC current to the displacement detecting elements, a circuit for controlling voltage for the oscillator, and amplifier for amplifying current flowing through the second capacitor. In this case, the output signal is supplied to a load through a transmission line of a DC electric power source for the amplifier.

DISPLACEMENT-ELECTRIC SIGNAL CONVERTER

BACKGROUND OF THE INVENTION

1. Field of the Invention

The present invention relates to a displacement-electric signal converter which converts displacements to corresponding electric signals, and more particularly to a displacement-electrical signal converter which converts process variables, produced as mechanical displacements, corresponding to, for example, flow rate, pressure, temperature and the like to systematic or uniform electric signals and is capable of transmitting the electric signals to a receiver means disposed at a remote place.

2. Description of the Prior Art

A conventional displacement-electric signal converter has its power source line and signal line are provided individually, that is, a four-wire system. Such a conventional converter has drawbacks that its cost becomes high, its installation is complicated because of the many lines and troubles are apt to occur.

SUMMARY OF THE INVENTION

It is a main object of the present invention to provide a displacement-electric signal converter which is capable of transmitting an electric signal obtained by converting displacement to a receiver with the so-called two-wire system in which a two-wire line is employed common to power source transmission and signal transmission.

It is another object of the present invention to provide a displacement-electric signal converter in which the zero point thereof is not shifted or moved even if its operative range is changed.

It is further object of the present invention to provide a device which produces an electric signal in proportion to displacement precisely without being affected by surrounding temperature and transmits the electric signal to a receiver positively and stably.

It is still further object of the present invention to provide a device which can easily attain an intrinsic safety.

Other objects, features and advantages of the present invention will be apparent from the following description taken in conjunction with the accompanying drawings in which like reference numerals represent like elements.

BRIEF DESCRIPTION OF THE DRAWINGS

FIG. 1 is an electric connection diagram showing one embodiment of the present invention;

FIG. 2 is a schematic diagram illustrating, by way of example, a differential inductance element employed in the example of the present invention depicted in FIG. 1;

FIG. 3 is a graph illustrating characteristics of the example shown in FIG. 1; and

FIGS. 4 to 7, inclusive, are respectively electric connection diagrams illustrating other embodiments of the present invention.

DESCRIPTION OF THE PREFERRED EMBODIMENTS

FIG. 1 is an electric wiring diagram showing one embodiment of the present invention. In the figure reference numeral 1 designates a displacement detecting circuit which detects process variables and produces corresponding electrical signals, the process variables being obtained as mechanical displacements. Reference numeral 2 indicates an oscillator, 3 a differential amplifier for controlling the voltage of an electric power source for the oscillator 2, 4 a range change circuit, 5 an amplifier for amplifying the electric signal derived from the displacement detecting circuit 1, 6 a constant-voltage circuit and 71 and 72 output terminals of the displacement-electric signal converter of this invention. Reference numerals 8 and 9 designate a load (receiver meter) and a voltage source (an electric power source) which are located at a place remote from the main device consisting of the displacement detecting circuit 1, oscillator 2, differential amplifier 3 and the like. The load 8 and the electric power source 9 are connected in series between the output terminals 71 and 72 through transmission lines 1. In this case the electric power source line 1 is also employed as the signal line 1, that is to say, the transmission system of this example is the so-called "two-wire system".

Reference characters L_1 and L_2 in the displacement detecting circuit 1 indicate a pair of coils forming a differential inductance element (inductor). In this case the number of turns of the coils L_1 and L_2 is selected equal to each other.

FIG. 2 shows, by way of example, a practical embodiment of the differential inductance element (inductor). In the figure reference numeral 11 indicates a core which consists of an E-shaped core member 12 and a rod like core member 13 the cross-sectional configuration of which is approximately rectangular. The coils L_1 and L_2 are respectively wound on the core member 13. Reference numeral 14 indicates a short-circuit ring mounted on the core member 13 between the coils L_1 and L_2 and reference character g a gap formed between the core member 13 and the center leg 12C of the core member 12 in which gap g the short-circuit ring 14 is disposed. The process variables are produced as mechanical displacements in a well-known conventional manner and thus obtained mechanical displacements are applied to the short-circuit ring 14 in this example. When the mechanical displacements are applied to the short-circuit ring 14, the ring 14 is moved or shifted to the left or right in accordance with the mechanical displacements to change the inductance between the coils L_1 and L_2 in differential manner.

Turning to FIG. 1, reference character S_0 in the displacement detecting circuit 1 shows a circuit portion which derives the sum and difference between currents i_1 and i_2 passing through the coils L_1 and L_2 . In the circuit S_0 reference characters D_1 to D_6 , inclusive, indicate diodes respectively, C_1 and C_2 capacitors and R_1 a resistor element. Free ends of the coils L_1 and L_2 connected in series are respectively connected to input terminals a and b of a rectifier circuit S_1 which consists of the diodes D_1 to D_4 as a bridge circuit, the connection point of the diodes D_1 and D_3 corresponding to the input terminal a and the connection point of the diodes D_2 and D_4 to the input terminal b . The capacitor C_1 is

inserted between output terminals *f* and *h* of the rectifier circuit *S*₁, namely the connection point of the diodes *D*₁, *D*₂ and the connection point of the diodes *D*₃, *D*₄. Reference character *T* in FIG. 1 designates a transformer a primary winding *n*₁ of which is used as an oscillation coil of the oscillator 2. The oscillation output of the oscillator 2 is obtained from a secondary winding *n*₂ of the transformer *T*. One end of the secondary (or output) coil *n*₂ is connected to the connection point of the coils *L*₁ and *L*₂, while the other end of the coil *n*₂ is connected to the output terminal *f* of the rectifier circuit *S*₁ through a capacitor *C*₄, diodes *D*₅ and *D*₆ connected in opposite polarities and a filter circuit *S*₂ consisting of the capacitor *C*₂ and the resistor *R*₁ connected in parallel.

With the displacement detecting circuit 1 constructed as set forth above, when the voltage *e* induced across the output coil *n*₂ of the transformer *T* has the polarity shown in FIG. 1 by symbols $\oplus$ and $\ominus$, current *i*₁ flows through the coil *L*₁, the diode *D*₃, the capacitor *C*₁ and the diode *D*₅, while current *i*₂ flows through the coil *L*₂, the diode *D*₂ and the diode *D*₆, namely the currents *i*₁ and *i*₂ flow in the coils *L*₁ and *L*₂ respectively.

When the polarity of the voltage *e* induced in the coil *n*₂ is reversed, the current *i*₁ and *i*₂ flow through the diode *D*₆, the capacitor *C*₂, the capacitor *C*₁, the diode *D*₄ and the coil *L*₂ and through the diode *D*₆, the capacitor *C*₂, the diode *D*₁ and the coil *L*₁ respectively. Consequently, current Δi passing through the capacitor *C*₁ is the difference between the currents *i*₁ and *i*₂ passing through the coils *L*₁ and *L*₂, a current flowing in the capacitor *C*₂ of the filter circuit *S*₂ is the sum of the currents *i*₁ and *i*₂. In this case if the impedances of the diodes, capacitors and resistor (element) are small enough as compared with those of the coils *L*₁ and *L*₂, the current *i*₁ and *i*₂ are respectively expressed as follows:

$$i_1 = e/(\omega L_{11})$$

$$i_2 = e/(\omega L_{21})$$

where ω represents an angular frequency of the voltage *e* and *L*₁₁ and *L*₂₁ impedance values of the coils *L*₁ and *L*₂.

Accordingly, the sum of the currents *i*₁ and *i*₂ and the difference therebetween are expressed as follows:

$$i_1 + i_2 = \frac{e}{\omega} \left(\frac{L_{11} + L_{21}}{L_{11} L_{21}} \right) \quad (1)$$

$$i_1 - i_2 = \frac{e}{\omega} \left(\frac{L_{21} - L_{11}}{L_{11} L_{21}} \right) \quad (2)$$

From the equations (1) and (2) the relationship between *i*₁, *i*₂ and *L*₁₁, *L*₂₁ is deduced as follows:

$$i_1 - i_2 = (i_1 + i_2) \frac{L_{21} - L_{11}}{L_{11} L_{21}} \quad (3)$$

It will be apparent from the equation (3) that if the sum of the currents *i*₁ and *i*₂ is kept constant, the difference between the currents *i*₁ and *i*₂ is proportional to the difference between the inductances *L*₁₁ and *L*₂₁ of the coils *L*₁ and *L*₂, namely to the amount of the displacement of the short-circuit ring 14 mounted on the core member 13 of the differential inductance element (inductor).

With the example depicted in FIG. 1 the sum of the currents *i*₁ and *i*₂ is delivered from the resistor element *R*₁ as the voltage *V*₁ corresponding to the sum of the currents and thus obtained voltage *V*₁ is supplied to the differential amplifier 3 which, in turn, controls the voltage for the oscillator 2 in such a manner that the sum of the currents *i*₁ and *i*₂ may be maintained substantially constant.

References *R*₂ to *R*₄ in the differential amplifier 3 indicate resistor elements respectively which are connected in series with one another. A constant voltage from a zener diode *D*₂ included in the constant-voltage circuit 6 is applied across the both ends of the series connection of the resistor elements *R*₂ to *R*₄. The connection point between the resistors *R*₂ and *R*₃ is connected to a positive input terminal $\oplus$ of the differential amplifier 3 while the negative input terminal $\ominus$ thereof is connected to one terminal *j* of the filter circuit *S*₂. The other terminal *f* of the filter circuit *S*₂ is connected to the connection point of the resistors *R*₃ and *R*₄. The output voltage of the differential amplifier 3 is applied to the oscillator 2 as its power source through a diode *D*₇ which is used for preventing passage of reverse current, whereby the oscillator 2 starts its oscillation operation. The oscillation output of the oscillator 2 is derived from the output coil *n*₂ of the transformer *T* and then applied to the displacement detecting circuit 1 to cause the currents *i*₁ and *i*₂ to flow in the coils *L*₁ and *L*₂ as explained above. In this example the power source voltage of the differential amplifier 3 is obtained from the constant-voltage circuit 6 which is supplied with current from the DC power source 9 through the transmission lines *l*.

The operation of the differential amplifier 3 will be hereinafter explained. As set forth above the voltage *V*₁ corresponding to the sum of the currents *i*₁ and *i*₂ passing through the coils *L*₁ and *L*₂ is applied to the input terminal $\oplus$ of the differential amplifier 3 while the voltage *V*₂ produced across the resistor *R*₃ is applied to the other input terminal $\ominus$ of the differential amplifier 3. The differential amplifier 3 produces at its output terminal a voltage corresponding to the difference ΔE ₁ between the voltages *V*₁ and *V*₂ but operates to reduce the difference voltage ΔE ₁ to substantially zero when the gain thereof is selected high enough. Accordingly, the differential amplifier 3 produces a substantially constant voltage as its output. The constant voltage of the differential amplifier 3 is applied to the oscillator 2 with a result that the output frequency of the oscillator 2 is substantially constant. Consequently, excitation current applied to the differential transformer, namely the sum of the currents flowing through the coils *L*₁ and *L*₂ can be controlled to be an approximately constant value. If the sum of the currents *i*₁ and *i*₂ is held constant, the difference Δi between the currents *i*₁ and *i*₂ which flow through the capacitor *C*₁ of the displacement detecting circuit 1 is exactly proportional to the amount of the displacement of the short-circuit ring 14 mounted on the core member 13 of the differential transformer as apparent from the equation (3).

In the range change circuit 4 shown in FIG. 1, reference characters *R*₆ to *R*₁₂, inclusive, denote range change resistors, respectively. The resistance values of the range change resistors *R*₆ to *R*₁₂ are respectively selected to have values corresponding to a decimal

code such, for example, as 1, 2, 4, 0.1, 0.4 and 0.8. Reference characters S_1 to S_7 inclusive, indicate switching elements. The resistor R_6 and the switching element S_1 , . . . and the resistor R_{12} and the switching element S_7 are respectively connected in series with each other and the respective series connections of the resistors R_6 to R_{12} and the switching elements S_1 to S_7 are connected to the capacitor C_1 of the displacement detecting circuit 1 in parallel with one another. As explained in connection with the displacement detecting circuit 1, as the short-circuit ring 14 of the differential inductance element is displaced or shifted to change the inductance between the coils L_1 and L_2 differentially, the difference current Δi flows through the capacitor C_1 correspondingly. In this case if one or more of the parallel switching elements S_1 to S_7 is closed a voltage ΔV expressed by $\Delta i R$ is produced across the resistor or resistors connected to the closed switching element. Since the resistors R_6 to R_{12} are selected to follow a decimal code as set forth above, the voltage ΔV can be changed with in the range of $0.1 \approx 7.0$ in steps of 0.1 by suitably closing one or more switching elements S_1 to S_7 , in other words, the range of the voltage ΔV can be variable.

In the constant-voltage circuit 6, reference character Q_1 indicates a transistor, Q_2 a field-effect transistor and D_8 a diode which is inserted between the base of the transistor Q_1 and one electrode of the Zener diode D_2 . The other electrode of the Zener diode D_2 is connected to the output terminal 72 through a feedback resistor R_{13} . The source and drain electrodes of the field-effect transistor Q_2 are connected to the base and collector electrodes of the transistor Q_1 respectively and the gate electrode of the field-effect transistor Q_2 is connected to the connection point between the diode D_8 and the Zener diode D_2 . With this circuit construction the gate of the field-effect transistor Q_2 is reverse biased by the forward voltage drop across the diode D_8 , so that a constant current is applied to the diode D_2 . As a result, the constant-voltage circuit 6 operates to keep the power source voltage for the amplifier substantially constant even if the load current I_0 changes.

In the amplifier circuit 5 reference numeral 51 designates a differential amplifier and Q_3 a transistor the base electrode of which is connected to the output terminal of the differential amplifier 51, the collector electrode of which is connected to the collector electrode of the transistor Q_1 and the emitter electrode of which is connected through a resistor R_{14} to one end of the feedback resistor R_{13} . Reference characters R_{15} and R_{16} indicate fixed resistors and R_{17} a variable resistor. These resistors R_{15} , R_{17} and R_{16} are connected in series and one end of the resistor R_{15} is connected to the emitter electrode of the transistor Q_1 and one end of the resistor R_{16} is connected to the output side of the feedback resistor R_{13} . The variable resistor R_{17} constitutes the zero point adjusting circuit of this device which will be explained later. The power source voltage for the differential amplifier 51 may be obtained from the constant-voltage circuit 6 which is supplied with current from the DC power source 9 through the transmission line 1. The input side $\oplus$ of the differential amplifier 51 is connected to one end of the movable contact of the variable resistor R_{17} while the other input side $\ominus$ is connected to the connection point of the switching elements S_1 to S_7 of the range change circuit 4.

The amplifier circuit 5, has its $\ominus$ input side supplied with the voltage ΔV produced in the range change circuit 4 while its $\oplus$ input side is supplied with, as a feedback voltage, the voltage corresponding to the voltage generated across the feedback resistor R_{13} due to the load current I_0 . The transistor Q_3 is driven by an output signal from the differential amplifier 51 to control the load current I_0 . The differential amplifier 51 operates to make the difference voltage ΔE_2 between the voltages applied to the input sides $\oplus$ and $\ominus$ thereof to be substantially zero if the gain of the differential amplifier 51 is made high enough. That is, although voltage applied to the input side $\oplus$ of the differential amplifier 51 is varied in accordance with the variation of the load current I_0 , the differential amplifier 51 operates to bring the voltage applied to its $\ominus$ input side approximately equal to that applied to its $\oplus$ input side. In this case since the voltage drops across the resistors R_2 and R_3 are selected substantially constant, the load current I_0 is controlled in such a manner that the variation of the voltage applied to the $\oplus$ input side of the differential amplifier 51, which is caused by the voltage drop across the resistor R_{13} due to the load current I_0 , becomes approximately equal to the voltage ΔV produced in the range change circuit 4. The voltage ΔV can be changed by selectively closing one or more of the switches S_1 to S_7 , so that the load 8 is supplied with current I_0 proportional to the amount of the displacement of the short-circuit ring 14 and in correspondence with the range through the transmission line which is also used for power transmission.

In a general process control system, a signal transmitted from a detector for detecting process variables to a receiver side is converted to a uniform or systematic electrical signal of, for example, $4 \approx 20$ milliamperes for the range of $0 \approx 100$ percent of the input signal of the detector. In the event that a base current of, for example, 4 milliamperes exists in the uniform or systematic electrical signal, when the displacement applied to the short-circuit ring 14 of the differential inductor is zero, namely the current Δi flowing through the capacitor C_1 of the displacement detecting circuit 1 is zero, the movable contact of the variable resistor R_{17} is previously set or adjusted to make the load current I_0 4 milliamperes. With such an adjustment the zero point is prevented from being moved or shifted even if the range is thereafter changed to vary the voltage ΔV produced in the range change circuit 4.

FIG. 3 is a graph showing one example of the experimental results with the device of the present invention shown in FIG. 1 in which the ordinate represents the load current in milliampere, the abscissa the distance X of the short-circuit ring 14 of the differential inductor in millimeter and the range change resistor R as a parameter. In the graph, a curve a_1 corresponds to the case where R is $5.1 \text{ k}\Omega$ (kilo-ohms); a curve b_1 the case where R $2.4 \text{ k}\Omega$; and curves c_1 and d_1 the cases where R are $1 \text{ k}\Omega$ and 500Ω , respectively.

With conventional apparatus when there is base current, zero point adjustment must be made every time when the range is changed.

According to the present invention, on the contrary, since the apparatus is adjusted in such a manner that the load current becomes a base current when an input signal is zero, the zero point is not shifted even when the resistor R is varied as apparent from the graph,

which will means that change of the range can be easily carried out. In addition, according to the present invention since an oscillation frequency of the oscillator 2 may be selected high such, for example, as 50 KHz, the values of the coils L_1 , L_2 and the capacitors can be made small. Consequently, the device is safe.

FIG. 4 shows another embodiment of the present invention in which similar references indicate similar elements or components of the example shown in FIG. 1. In the example shown in FIG. 1 the positive electrode or anode of the diode D_5 of the displacement detecting circuit 1 is directly connected to the output terminal f of the rectifier circuit S_1 , while in FIG. 4 example the anode of the diode D_5 is connected to the output terminal f through a resistor R_1' the resistance value of which is substantially equal to that of the resistor R_1 , connected to the cathode of the diode D_6 . Further, in FIG. 4 example the input terminals $\oplus$ and $\ominus$ of the differential amplifier 3 are respectively supplied with a voltage produced in a resistor R_{19} and a voltage across the capacitor C_2 , the resistor R_{19} being connected between the anode of the diode D_5 and the $\oplus$ input terminal of the differential amplifier 3, and the capacitor C_2 being inserted between the anode of the diode D_5 and the $\ominus$ input terminal of the differential amplifier 3. The differential amplifier 3 of this embodiment thus supplied with the voltages at its input terminals operates to make the voltage difference between the voltages applied thereto to be substantially zero, to thereby control a power source voltage applied to the oscillator 2 so that it remains approximately constant.

With such an arrangement currents i_1 and i_2 respectively flow through the diodes D_5 and D_6 through the resistors R_1 and R_1' of equal resistance value, namely the currents i_1 and i_2 flow through the rectifier circuit S_1 symmetrically, so that an apparatus which is less affected by noises as compared with the FIG. 1 example is provided.

Although in FIG. 4 the range change circuit 4 is exemplified only by a single variable resistor R , its detailed construction is substantially the same as that shown in FIG. 1.

With this arrangement, it can be also possible as in the case of the FIG. 1 example that the range of the voltage ΔV may be varied by changing the value of the resistor R without adjusting the zero point and also that the zero point may be adjusted by suitably changing the variable resistor R_{17} . Other construction, features and operations of FIG. 4 example are substantially the same as those of the FIG. 1 example, and the explanation is omitted for the sake of simplicity.

FIG. 5 shows another modified form of the present invention in which like references designate like elements or components to those of the foregoing examples. The main difference in construction between this example and the FIG. 4 example resides in the displacement detecting circuit 1 and the other constructions are substantially same to those of FIG. 4 example.

In the displacement detecting circuit 1 of the FIG. 5 example, reference character n_2 indicates the secondary coil of the transformer T which is divided approximately at its center into two coil portions n_{21} and n_{22} . One end of the coil, for example, n_{21} is connected to the input terminal a of the rectifier circuit S_1 and one end of the other coil n_{22} to the input terminal b of the recti-

fier circuit S_1 . The center point of the output coil n_2 is connected to the output terminal f of the rectifier circuit S_1 and one sides of the diodes D_1 and D_2 are connected to the output terminal f through the resistors R_1 and R_1' which have the same resistance values. In this example the capacitor C_2 is connected to the series circuit of the resistors R_1 and R_1' and in parallel therewith. One end this parallel connection is connected to the $\ominus$ input terminal of the differential amplifier 3 and the other end is connected to the $\oplus$ input terminal of the amplifier 3 through the resistor R_{19} .

According to the example with the displacement detecting circuit 1 constructed as set forth above, current corresponding to the sum of the inductances of the coils L_1 and L_2 also flow through the capacitor C_2 while current proportional to the difference of inductance flows through the capacitor C_1 . The differential amplifier 3 operates to equalize the voltage across the capacitor C_2 and the voltage across the resistor R_{19} , to thereby control the power source voltage to the oscillator 2 with a result that current passing through the capacitor C_2 is maintained approximately constant.

The currents i_1 and i_2 flowing through the capacitor C_1 of the FIG. 4 example are different in phase by 180° but currents i_1 and i_2 of the FIG. 5 example are in phase. Consequently, the capacity values of the capacitors C_1 and C_2 of this example can be made small as compared with those of FIG. 1 example and the rectifier circuit S_1 may be manufactured at a low price.

FIG. 6 is a still another modified form of the present invention in which similar reference numerals to those of the foregoing examples represent similar elements or components. In the examples shown in FIGS. 1, 4 and 5 the mechanical displacement is converted into corresponding electric signals by means of inductors, corresponding to inductance changes thereof but in the FIG. 6 example the mechanical displacement is converted into a corresponding electrical signal by the utilization of capacitors, corresponding to capacitance changes.

In the FIG. 6 example reference numeral 15 designates a movable electrode plate one end of which is connected to the output coil n_2 of the transformer T and 16 and 17 designate fixed electrode plates adjacent the movable electrode plate 15 but spaced therefrom. The fixed electrode plates are respectively connected to the output terminals a and b of the rectifier circuit S_1 , whereby a differential capacitance type displacement detector is formed. The other construction and operation of this example are substantially same to those of the examples shown in FIGS. 4 and 5.

With such an arrangement when the movable electrode plate 15 is displaced in response to the mechanical displacement, the capacitance values C' and C'' between the movable electrode 15 and the fixed electrodes 16, 17 are varied differentially, whereby current in accordance with the capacitance variation flows through the rectifier circuit S_1 . In this case the current Δi corresponding to the difference between the capacitance values C' and C'' flows in the capacitor C_1 , while the current corresponding to the sum of the capacitance values C' and C'' flows in the capacitor C_2 as explained in connection with FIG. 1 example. The differential amplifier 3 of this example operates to equalize the voltage across the capacitor C_2 with that

across the resistor R_{19} , to thereby control the power source voltage for the oscillator 2 as in the foregoing examples.

FIG. 7 shows a further modified form of the present invention. In the figure reference numeral 1 designates the displacement detecting circuit which includes coils L_1 and L_2 , 2 the oscillator, 3 a control circuit, corresponding to the differential amplifier 3 in the foregoing examples, to control the power source voltage for the oscillator 2 and 5 the current amplifier circuit which employs a blocking oscillator.

The oscillator 2 of this example is a back coupling type oscillator employing a transistor Q_4 . This oscillator 2 oscillates at the natural frequency of a tuning circuit consisting of a feedback winding n_{1f} of the transformer T connected to the base of the transistor Q_4 and a capacitor C_4 connected in parallel to the winding n_{1f} . The oscillation amplitude of the oscillator 2 is changed in accordance with the magnitude of the power source voltage applied thereto. The oscillator 2 is supplied with a voltage from a power source including the Zener diode D_2 which is, in turn, supplied with a current from the DC power source 9 through the transmission line l . The control circuit 3 comprises a transistor Q_5 and is inserted between the oscillator 2 and the Zener diode D_2 . The base of the transistor Q_5 is connected to the connection point of a resistor R_{11} and a Zener diode D_{21} through a resistor R_{21} , the series connection of the resistor R_{11} and the Zener diode D_{21} being connected to the Zener diode D_2 in parallel, whereby the base of the transistor Q_5 is supplied with a constant reference or standard current I_s . The inductance values of the coils L_1 and L_2 in the displacement detecting circuit 1 is differentially changed in accordance with the displacement of the short-circuit ring 14 as described above, so that the capacitor C_1 permits therethrough passage of the current corresponding to the difference between the inductance values of the coils L_1 and L_2 while the capacitor C_2 permits therethrough passage of the current corresponding to the sum of the inductances of the coils L_1 and L_2 . In this example the output terminal j of the rectifier circuit S_2 is connected to the base of the transistor Q_5 of the control circuit 3 to apply the current corresponding to the sum of the inductances of the coils L_1 and L_2 to the transistor Q_5 in the counter-direction to the reference current I_s as shown by a dotted line in the figure. The current amplifier circuit 5 includes a blocking oscillator 51 which has a transistor Q_6 and coils n_{1f} and n_{11} . To the input side of the blocking oscillator 51 is connected the aforementioned filter circuit S_1 . The power source of the blocking oscillator 51 is obtained from the Zener diode D_2 which is supplied with current from the DC power source 9 through the transmission line l as described above, while a bias current I_B is applied from the Zener diode D_{21} through a resistor R_{61} . In the figure reference numeral 52 is a circuit including transistors Q_7 and Q_8 , which rectifies and amplifies an output of the blocking oscillator 51 produced at the secondary winding n_{12} of a transformer T_1 to control the load current I_0 flowing through the transmission line l . Reference character R_{22} indicates a variable resistor which is connected between the output end of the feedback resistor R_{13} and the output side of the filter circuit S_1 and feedbacks current I_f due to a voltage produced in the resistor R_{13} .

by the load current I_0 to the input side of the blocking oscillator 51.

With the arrangement shown in FIG. 7 the current corresponding to the sum of the inductances of the coils L_1 and L_2 are compared with the reference current I_s from the Zener diode D_{21} and the difference current therebetween is applied to the base of the transistor Q_5 , so that as the sum current is increased the base current of the transistor Q_5 is decreased with a result that the voltage between the collector and emitter of the transistor Q_5 is increased to reduce the power source voltage to the oscillator 2, while as the sum current is decreased to enhance the base current of the transistor Q_5 , the voltage across the collector-emitter of the transistor Q_5 is lowered with a result that the voltage to the oscillator 2 is enhanced and the power source voltage for the oscillator 2 is controlled to maintain the sum current approximately constant. The current passing through the capacitor C_1 which corresponds to the difference between the inductances of the coils L_1 and L_2 is fed to the blocking oscillator 51 of the current amplifier circuit 5, whereby the voltage across the capacitor C_5 of the blocking oscillator 51 is increased. As a result, the bias current I_B flows as a base current of the transistor Q_6 , so that the transistor Q_6 is made conductive by blocking oscillation thereof. When the transistor Q_6 is made conductive and its output is applied to the transistor Q_7 through the same transformer T_1 , the current as to the emitter current of the transistor Q_7 flows in its collector through resistors R_4 and R_5 . The pulse voltage caused thereby is smoothed by a capacitor C_6 connected to the resistor R_4 and then supplied to the base of the transistor Q_8 which, in turn, controls the load current I_0 flowing through the transmission line l in accordance with the voltage supplied to its base. The load current I_0 causes generation of a voltage across the resistor R_{13} which produces the feedback current I_f flowing through the resistor R_{22} . As a result, the input current is amplified such that the input current is balanced with the feedback current I_f . Consequently, the output current I_0 flowing through the load 8 corresponds to the difference between the inductances of the coils L_1 and L_2 .

Since in the present example the current corresponding to the difference between the inductances of the coils L_1 and L_2 is amplified by the current amplifier circuit employing the blocking oscillator as set forth above, the present example is less affected by variations of temperature of the surroundings.

It is possible in FIG. 7 example to employ capacitors shown the FIG. 6 instead of the coils L_1 and L_2 .

A change of the range is obtained by controlling variable resistor R_{22} .

It will be apparent that many modifications and variations may be effected without departing from the scope of the novel concepts of this invention.

We claim as our invention:

1. A displacement-electric signal converter comprising:

a pair of displacement sensing means connected in series and having impedances which are differentially changed in accordance with a mechanical displacement;
a rectifier circuit consisting of a plurality of diodes connected as a bridge circuit, said series-con-

nected pair of displacement sensing means being connected between the input terminals of said bridge circuit, first and second capacitors, said first capacitor being connected between the output terminals of said bridge circuit, said second capacitor having means connecting one end to the connection point of said pair of displacement sensing means and its other end connected to one of the output terminals of said bridge circuit;

a current corresponding to the difference between the impedances of said pair of displacement sensing means being obtained from said first capacitor;

a current corresponding to the sum of said impedances being obtained from said second capacitor;

an oscillator with its output side coupled to said pair of displacement sensing means for applying A. C. current to said pair of displacement sensing means;

a differential amplifier circuit with one input terminal connected to said second capacitor, the other input terminal of said differential amplifier supplied with a constant voltage and the output side of said differential amplifier connected to said oscillator for providing the electric power source voltage for said oscillator to maintain substantially constant current flowing through said second capacitor;

a second amplifier to which the voltage across both terminals of said first capacitor is supplied for amplifying current flowing through said first capacitor; and

a means including a D. C. electric power source of said second amplifier for transmitting the output signal of said second amplifier to a load.

2. A displacement-electric signal converter as claimed in claim 1 in which said pair of displacement sensing means consist of a pair of differential inductors.

3. A displacement-electric signal converter as claimed in claim 1 in which said pair of displacement sensing means consist of a pair of capacitors.

4. A displacement-electric signal converter as claimed in claim 1 in which said second amplifier is a second differential amplifier one input terminal of which is supplied with voltage across said first capacitor and the other input terminal of which is supplied with a feedback voltage, said second differential amplifier controlling a load current to make the voltage difference between said voltages applied to its input terminals substantially zero.

5. A displacement-electric signal converter as claimed in claim 1 which comprises a circuit for comparing current passing through said second capacitor with a reference current and controlling the electric power source voltage of said oscillator in accordance with the difference between said currents, and a third amplifier employing a blocking oscillator for amplifying current passing through said first capacitor.

6. A displacement-electric signal converter as claimed in claim 1 which further includes a range change circuit connected in parallel to said first capacitor for changing the range of voltage across said first capacitor.

7. A displacement-electric signal converter as claimed in claim 6 in which said range change circuit includes a plurality of circuits each comprising a resistor and a switching element connected in series, and each of said circuits connected in parallel with said first capacitor.

8. A displacement-electric signal converter as claimed in claim 4 which includes a zero point adjusting circuit which adjusts the zero point of the converter by controlling the feedback voltage from said second differential amplifier.

9. A displacement-electric signal converter as claimed in claim 8 in which said zero point adjusting circuit consists of a variable resistor element.

10. A displacement-electric signal converter as claimed in claim 5 in which a means is provided for changing the range by varying a feedback current of said blocking oscillator.
